UNITED STATES PATENT OFFICE

IRVING C. HICKS, OF TOPEKA, KANSAS, ASSIGNOR OF ONE-HALF TO HENRY V. STEVENS,
OF TOPEKA, KANSAS

STEAM BOILER

Application filed June 8, 1929. Serial No. 369,446.

My invention relates to steam boilers and more particularly to the door end elements of steam boilers, the principal objects of the invention being to promote the circulation of hot water through the door end element and the boiler, to enhance the movement of products of combustion over the door sheets, to relieve the joint between the inner door sheet and the crown sheet of excessive heating influence, and to connect the back head and door sheet in such a manner as to provide for different degrees of expansion of said sheets.

A further object of the invention is to adapt sheet connecting means for facilitating the mounting of instruments on the end sheet of a boiler.

In accomplishing these and other objects of the invention, I have provided improved details of structure, the preferred forms of which are illustrated in the accompanying drawings, wherein:

Fig. 1 is an elevation half in section of the door end of a boiler.

Fig. 2 is a longitudinal central section through the door end of the boiler including portions of the casing, crown sheet and combustion chamber.

Fig. 3 is an enlarged detail section of a portion of back and door sheets and my improved method for connecting the same.

Referring in detail to the drawings:

1 designates generally the outer shell or arcuate casing of a boiler, 2 a crown sheet forming part of the inner casing spaced from the outer casing to form water legs and comprising the side walls of the combustion chamber, and 3 designates generally a rear end wall comprising a fire door sheet 4 and an end sheet 5 having registering central openings to comprise the door 6 of the rear wall.

The fire sheet 4 extends substantially in a plane adapted to intersect the crown sheet, and has an upper edge provided with a de-

pressed portion 7 having a return bend at its margin forming an attaching flange 8 adapted to be secured to the end edge portion 9 of the crown sheet.

In order to effect this connection the crown sheet is elongated so that its end 9 will project to and preferably beyond the plane of the fire door sheet 4, whereby the outwardly swelling portion 7 of the door sheet may extend inwardly of the water leg formed by the door sheet, and the end sheet and the edge of the attaching flange 8 lies substantially in the plane of the sheet.

The annual flange 10 at the central door opening of the door sheet 4 is also formed in a particular manner, being curved rearwardly from the plane of the sheet whereby products of combustion rising in the chamber may move readily over the arcuate door facing into contact with the straight portion 11 of the inner sheet between the door facing and the recessed portion 7, and will tend to move across the recess into contact with the crown sheet at points spaced from the seam of the crown sheet with the door sheet.

The end sheet is formed in conformity with the special construction of the door sheet, and for this purpose is provided with a boss-like protuberant or swelling portion 12 coinciding with the arcuate bent portion 7 of the door sheet but bent on an arc having a greater radius than the arc on which said door sheet portion is bent, whereby the projection of the portion 7 into the water leg is compensated for and constriction of the passage is avoided.

The flange 13 at the door opening of the end sheet is arcuately out-bent to form a convex protuberant portion or ring around the opening and is then indent at its inner edge to overlie the flange of the door sheet for attachment thereto to seal the joint at the opening between the door and end sheets, the construction varying from common practice.

in that the outer face of the end sheet bulges at the opening.

The invention further includes specially applied means for connecting the end and door sheets, including stay bolts 14 positioned in perpendicular relation with the portions of the surface of the door sheet in which they are located.

I accomplish the above named result partly by the provision of the described bends in the sheets, and the arrangement is possible because of the manner in which I form the inner sheet.

Attention is called to the position of the stay bolts adjacent the door opening, the upper stay bolts 15 and 16, for example being inclined downwardly inwardly, and the stay bolts 17 and 18 below the opening being inclined upwardly inwardly, and thus vary from common practice.

The edges forming the joints between the door sheet and the crown sheet, and the end sheet and the door sheet at the opening, may be secured by means included in classes comprising plugs, patch bolts, rivets, and seams made by fusion welding.

The stay bolts preferably are of flexible character adapted to my particular form of end member, and the door sheet preferably has screw-threaded apertures 19 to receive the screw-threaded ends 20 of the bolts, and the outer sheets have larger apertures 21 provided with tapering walls 22 in which apertured sockets 23 are fixed as by welding to receive the spherical heads 24 of the bolts.

The sockets are mounted with their outer edges substantially registering with the outer face of the end sheet and project into the water leg, and nuts 25 may be screw-threadedly mounted in the sockets to retain the bolts, and fixed in the sockets by welds 26.

In assembling a boiler having the improved features described, the sockets are fixed in the end sheet, the bolts are inserted through the sockets into the door sheet apertures, the spherical heads seating on the tapering walls of the sockets, and the nuts are applied to retain the stay bolts against outward movement and thus retain the sheets in spaced relation. The heads of the stay bolts are thus substantially recessed in the end sheet so that the outer surface thereof may be free for the door frame and for the support of instruments and the like.

In use, the products of combustion will contact the entire surface of the door sheet between the opening and the crown sheet with the exception of the relatively small portion in the depression between the door sheet and the crown sheet, whereby a maximum heating effect on the water in the space between the sheets is afforded. The full advantage of the water capacity around the door opening is thus availed of, the water is heated more rapidly, circulation from the

end member through the boiler is promoted and increased, and water circulation tends to prolong the life of the fire and door sheets since mud and scale are prevented from lodging around the fire door.

The construction illustrated differs from the ordinary construction in important particulars, one being the fact that in ordinary construction a door sheet is formed with inward projections which direct the fire away from the sheet as it passes from the opening upwardly toward the crown sheet, whereas the outward pressing of the door sheet at the opening in my structure provides for the guidance of the flames and gases into contact with the door sheet.

Another distinction is that in ordinary construction, the seam between the door sheet and crown sheet is in such a position that the flames contact the seam and tend to disrupt it, whereby leaks may be produced, whereas applicant projects the seam into the water leg and thus offsets it from the path of the flames and hot gases.

Attention is called to the fact that the end sheet is formed to compensate for the novel structure of the door sheet so that constriction of the water leg due to depression of the door sheet at its upper edge is avoided, and ample capacity at the door opening is afforded.

The welding of the cap nuts in the sockets, which is preferably done by fusion welding, not only retains the nuts but seals the sockets to prevent escape of steam.

What I claim and desire to secure by Letters Patent is:

1. In a steam boiler, an end wall having a door opening and including a door sheet having a substantially plane inner surface curved rearwardly at the opening, and an end sheet having an annular flange curved outwardly and then inwardly to overlap the door sheet to provide increased water capacity around the door opening exteriorly of the boiler at said opening.

2. In a boiler, an end wall including a door sheet having a door opening and a substantially plane inner surface curved rearwardly at the opening, and an end sheet spaced from the door sheet and curved outwardly and then inwardly at the door opening complementary to the curvature of the inner sheet to provide a connection between the sheets substantially semi-circular in cross section whereby expansion and contraction between the sheets is compensated for by the curvature of the sheets.

3. In a boiler, including a casing sheet and a crown sheet, a door sheet having a plane inner surface curved rearwardly about a door opening in the sheet, and a forwardly extending flange offset rearwardly from the inner plane of the door sheet for securing the door sheet to the crown sheet so that products of

combustion playing over the inner surface of the door sheet will not contact the joint formed thereby, and an end sheet spaced from the door sheet having an outwardly and inwardly curved flange overlapping the flange of the door sheet and having an offset portion opposite said offset flange to provide uniform spacing between the sheets.

4. In a boiler, an end wall having a substantially plane inner surface, a door opening therethrough, and a water leg enlarged outwardly of the boiler circumferentially of the door opening for providing increased water capacity about said opening.

15 In testimony whereof I affix my signature.

IRVING C. HICKS.
